WINDOW CONSTRUCTION

Filed Oct. 3, 1921

2 Sheets-Sheet 2

UNITED STATES PATENT OFFICE.

JOSEPH SYLVAN, OF CICERO, ILLINOIS.

WINDOW CONSTRUCTION.

Application filed October 3, 1921. Serial No. 505,104.

To all whom it may concern:

Be it known that I, JOSEPH SYLVAN, a citizen of the United States, and a resident of Cicero, in the county of Cook and State 5 of Illinois, have invented certain new and useful Improvements in Window Constructions; and I do hereby declare that the following is a full, clear, and exact description thereof, reference being had to the accompanying drawings, and to the letters of 10 reference marked thereon, which form a part of this specification.

This invention relates to improvements in window constructions and consists of the 15 matters hereinafter described and more particularly pointed out in the appended claims.

One of the objects of the invention is to provide a window construction wherein the 20 sash are vertically slidable in the frame, with the top sash of one set of sash so connected with the bottom sash of another set of sash, that said top and bottom sash act as the counter balance for each other.

Another object of the invention is to improve the construction of the means providing the guides between the sash and the frame, said means being adjustable to eliminate rattling of the sash in the frame. 25

Other objects of the invention as well as the many advantages thereof will more fully appear as I proceed with my specification.

In the drawings:—

Figure 1 is a view in elevation of two sets of window sash embodying my invention, as viewed from the inside of a room.

Figure 2 is a horizontal sectional view through Fig. 1 on the line 2—2 thereof;

Figure 3 is a vertical sectional view on an enlarged scale through one set of sash and associated frame parts, the plane of the section being indicated by the line 3—3 of Fig. 1;

Figure 4 is a horizontal sectional view through the lintel or head of the frame as taken on the line 4—4 of Fig. 3;

Figure 5 is an enlarged horizontal detail sectional view through one of the window 50 jambs as taken on the line 5—5 of Fig. 1;

Figure 6 is a detail perspective view of one corner of a window sash and will be more specifically referred to later;

Figure 7 is a diagrammatic perspective

view showing the manner of attaching the 55 window sash to their associated shafts in the lintel or head of the window frame.

Referring now in detail to that embodiment of the invention illustrated in the accompanying drawings:—5 indicates as a 60 whole, a window frame for a double set of window sash. Said frame includes upright side jambs 6—6, intermediate upright mullion 7, a head or lintel 8 and a sill 9 connected together in any suitable manner. 65

Each set of window sash comprises top and bottom window sash 10—10^a, 11—11^a respectively, and fixed to the side member of each sash is a laterally extending vertical flange 12, forming a part of an angle 70 bar imbedded in the side of the sash. Said flange may extend the full length of said sash if so desired.

Mounted on the side faces of the jambs and mullion are upright sheet metal channel 75 members 13. Each channel comprises a bowed or arched back wall 14, and side walls 15 and 16 respectively which terminate in oppositely facing flanges 17—18 arranged at right angles to said side walls. Associated with each channel and positioned between the flanges thereof, is a U-shaped sheet metal parting strip 19 which includes side flanges 20 and a web 22; the side flanges 20 engage in grooves 21 in the back wall 14 85 of the channel, and the web 22 is arranged in the plane of but is spaced from the edges of the flanges 17 and 18 to define therewith spaced slots 23—23 in which the flanges 12 of the window sash extend in a manner providing a guided sliding bearing for the 90 same.

In the web 22 of each U-shaped parting strip 19 is provided a plurality of vertically spaced countersunk holes 24 to receive the 95 heads of screws 25. These screws extend through registering holes in the back wall of the channels and are screwed into the wood of the jambs and mullion. To finish off the appearance of the jambs and mullion 100 after the channels have been applied, I provide the moulding strips 6^a, 7^a respectively. Should the slots 23 defined by the flanges 17 and 18 of the channels together with the web 22 of the U-shaped strip 19 be 105 too wide for the flanges 12 of the sash so that the same would rattle under wind pressure, said slots may be adjusted or re-

stricted by tightening up on the screws 25. This will draw the web 22 inwardly and through the side flanges 20, will tend to straighten out the arched or bowed back 5 wall and thus cause the flanges 17 and 18 of the channels to more closely approach each other until the desired width of slots 23 is attained.

In the head of the window frame is provided a horizontally elongated sheet metal box 26, of a depth a trifle greater than the width of the channels 13, as shown in Fig. 3. In said box are two horizontal shafts 27—28, arranged in the plane of the top 10 and bottom window sash. In the bottom wall of this box are provided openings 29 in line and communicating with the top end of each channel member 13. Fixed to each shaft 27—28 above the channels 13 are narrow 15 drums or grooved wheels 30—30^a and 31—31^a respectively.

Secured to the bottom sash 10^a of one set of sash are flexible members or cables 32 which are wound in one direction upon the 20 drums 30 on one shaft 27 and fixed to the top sash 11 of the other set are flexible members or cables 33, which are wound in an opposite direction upon the drums 30^a on the same shaft. The top sash 10 of the first set of sash and the bottom sash 11^a of the other set of sash also have flexible members or cables 34—35 respectively secured to them and wound in opposite direction upon the drums 31—31^a on the other shaft 28. This connection 25 between the shafts and sash is clearly shown in the diagram illustrated in Fig. 7. From this diagram it is apparent that the top sash of one set counter balances the bottom sash of the other set and vice versa, so that when one lower sash is raised or slid 30 upwardly in the window-frame, the other top sash descends. In attaching the flexible members 32—33—34 and 35 to their respective sash, I prefer to attach them to the flanges 12 thereof near the bottom end and for that purpose I provide a plurality of 35 holes 12^a in said flanges so that adjustments may be made for any inequalities as may exist in the length of flexible members used.

It is apparent that the flexible members 40 are located within the channels 13, so that all that appears to the observer is the sliding window sash in the frame. Should it be desired, the two sets of sash may be arranged 45 in frames spaced a distance from each other instead of being closely adjacent as shown, and in that case all that is necessary is to provide the proper length of shaft.

As my improved construction eliminates 50 the use of counter-balancing weights, I do not need to provide the usual boxlike jambs and mullion for said weights. Thus the mullions may be made narrower for the greater admission of natural light, and the 55 cost of the frames is greatly reduced.

Furthermore, the complete frame and sash may be assembled in the shop, ready for installation upon the job.

The sash operate easily and without binding and by means of the channel construc- 70 tion mentioned.

While in describing my invention I have referred to certain details of construction and arrangement of parts as well as in the form thereof, I do not wish to be limited thereto except as may be pointed out in the appended claims.

I claim as my invention:—

1. In combination with a plurality of sets of sash, each set comprising an upper and a lower sash, means providing frame members in which said sash are vertically slidable, a pair of shafts arranged in the top ends of said frame members, circular members on each pair of shafts, means connecting the bottom sash of one set and the top sash of another set with the circular members on one shaft, and means connecting the bottom sash of the second set and the top sash of the first set with said circular members on the second shaft, so that when one sash of one set is moved vertically the other sash of the other set moves simultaneously therewith in an opposite direction and counterbalances the same.

2. In combination with means providing a window frame member, hollow jamb members in the frame having vertically arranged slots therein, two sets of sash, each set comprising an upper and a lower sash, vertically movable in said frame, means on said sash extending through the slots of the hollow jamb members and into the interior thereof and guiding the movement of the sash with reference to said jamb members, two shafts arranged in the top end of said frame member and extending parallel with said sash, drums on each shaft, and means located in said hollow jamb members and connecting the bottom sash of one set and the top sash of another set with said drums, so that when one sash of one set is moved vertically in one direction the other sash of the other set moves simultaneously therewith in an opposite direction and counterbalances the same.

3. In combination with means providing a window frame member, hollow jamb members in the frame having vertically arranged slots therein, sets of top and bottom window sash vertically movable in said frame, means on said sash extending through the slots of the hollow jamb members and into the interior thereof and guiding the movement of the sash with reference to said jamb members, a shaft arranged in the top end of said frame member, drums on said shaft, flexible members secured to the guide means of the bottom sash of one set of sash disposed within the jamb members and wound in one direction upon some of said drums, and simi- 125 130

lar members secured to the guide means of the top sash of another set of sash, and wound in the opposite direction upon the other of said drums, so that when one of said 5 sash is moved vertically, in one direction, the sash connected thereto moves simultaneously therewith in an opposite direction and counterbalances the same.

4. In combination with means providing 10 a window frame having side jambs and an intermediate mullion, two sets of sash, each set comprising an upper and a lower sash, vertically slideable in said jambs and mullion, two shafts journalled in the top of said 15 frame, drums fixed to said shafts, there being two pairs of drums on each shaft, one pair of drums on one shaft being associated with the bottom sash of one set and the other pair of drums on said shaft being 20 associated with the top sash of the other set, the drums on the other shaft being likewise connected to the other top and bottom sash, and flexible means wound about the respective pairs of drums on each shaft, in opposite 25 directions and connected respectively to the bottom sash of one set and the top sash of the other set.

5. In a window construction, the combination of a window frame having side frame 30 members, jamb rails fixed to said side frame members, said rails each comprising a sheet metal channel having oppositely facing flanges, and a U-shaped sheet metal parting strip in the jamb rail channel and defining 35 with the flanges thereof laterally spaced slots to receive parts of window sash to guide the same in their vertical sliding movement with respect to said jamb-rails, and means for securing said parting strip in 40 position, said means being capable of being actuated to produce a relative movement between said channel flanges and said parting strip to determine the width of said slots.

6. In a window construction, the combination of a window frame having side frame 45 members, jamb rails fixed to said side frame members, said rails each comprising a sheet metal channel having oppositely facing flanges, a U-shaped sheet metal parting strip 50 in the jamb rail channel and defining with the flanges thereof laterally spaced slots to receive parts of window sash to guide the same in the vertical sliding movement with

respect to said jamb rails, and means passing through the U-shaped parting strips and jamb rail and into the side frame members to hold said jamb rail and strip in position, said means being capable of being actuated to produce a relative movement between said channel flanges and said parting strip to determine the width of said slots. 55 60

7. In a window construction, the combination of a window frame having side frame members, jamb rails fixed to said side frame members, said rails each comprising a sheet metal channel having an outwardly bowed back wall and oppositely facing flanges, and a parting strip in the jamb rail channel and defining with the flanges thereof, laterally spaced slots to receive parts of the window sash to guide the same in the vertical sliding movement with respect to the jamb rails, and means associated with the parting strip for securing the channel and parting strip to the side frame members, said means acting in conjunction with the parting strip to flex the channel to vary the width of said slots. 65 70 75

8. In a window structure comprising a frame having a jamb portion, the combination of a jamb rail and screws securing said rail to said jamb, said rail comprising a sheet metal channel having a transversely bowed back wall and two side walls and flanges extending inwardly toward each other from said side walls, the edges of said flanges being spaced apart, and a screw receiving parting strip located between the edges of the channel flanges and defining therewith two laterally spaced slots, said parting strip also engaging the intermediate part of the bowed back wall and being adapted to apply pressure thereto upon tightening of the screws to cause the flanges of the channel strip to more closely approach 90 the parting strip and define the effective opening of said slots. 95

In testimony that I claim the foregoing as my invention, I affix my signature in the presence of two witnesses, this 26th day of September, A. D. 1921. 100

JOSEPH SYLVAN.
